UNITED STATES PATENT OFFICE.

JOHN F. JESSEMAN, OF LYNN, MASSACHUSETTS.

BUFFING-MACHINE.

No. 811,504.

Specification of Letters Patent.

Patented Jan. 30, 1906.

Application filed April 25, 1905. Serial No. 257,313.

To all whom it may concern:

Be it known that I, JOHN F. JESSEMAN, of Lynn, in the county of Essex and State of Massachusetts, have invented certain new and useful Improvements in Buffing-Machines, of which the following is a specification.

This invention relates to buffing-machines; and its object is to provide a machine of this character with a plurality of buffing-rolls adapted to perform work of different characters rigidly supported so that yielding or springing of one end of the roll is impossible and mounted in such a manner with relation to each other that a shoe or other article to be acted upon by the buffing-rolls may be moved from engagement with one to engagement with the other by a simple movement in a vertical plane without necessitating a lateral movement and shifting of the operator's position.

The invention consists in the improved machine hereinafter described and claimed, and illustrated in the accompanying drawings, in which—

Figure 1 represents a front elevation of a machine embodying my invention. Fig. 2 represents a side elevation of the same. Fig. 3 represents a vertical section on line 3 3 of Fig. 2.

The same reference characters indicate the same parts in all the figures.

The machine comprises a pair of vertical frames *a a*, which are mounted at a suitable distance apart and connected by a cross-bar *b* and shafts *c d* of the buffing-rolls and driving-shaft *e*. Shafts *c d* are horizontally arranged between the frames and extend from side to side of the machine, their opposite ends being supported without possibility of yielding in rigid bearings *f g*, respectively, mounted on the frames. On these shafts are fixed buffing-rolls *h i*, which are cylindrical in form and are placed over the shafts so as to be rigidly supported thereby throughout their whole extent, each end of the rolls being supported with equal rigidity. As is evident from Figs. 2 and 3, the shaft *c* and roll *h*, carried by it, are supported above and forward of the shaft *g* and roll *i*, while the rolls are mounted on the shafts in corresponding lateral relations, so that the two rolls are located at the same distance from one of the side frames—that is, the rolls are arranged in the same vertical zone—and as they are seen in front elevation appear to be arranged with one vertically

above the other. They are also quite close together as compared with their distance from the base of the machine, above which they are held at not greatly unequal distances, 60 one roll being about at the level of the breast of the operator, while the other is slightly higher.

The shafts *c d* are driven independently from the driving-shaft *e* by pulleys *j k*, the first of which drives shaft *c* through belt *l* and pulley *m* on shaft *c*, while pulley *k* drives shaft *d* through a similar belt *n* and pulley *o*. Fast and loose pulleys *p p'* are arranged on the driving-shaft for receiving a belt by which 70 said shaft may be driven.

r is an air trunk or duct which has inlet-openings *s t* adjacent the buffing-rolls and which extend downward and opens into a fan-casing *u*, in which is located a fan connected to and driven by shaft *c*. As the fan revolves it expels air from the outlet *v* of the fan-casing and draws in the air through duct *r* and openings *s t*, thereby sucking in and carrying off the dust caused by the abrading 80 action of the buffing-rolls.

The rolls are provided with coverings of abrasive material and are preferably adapted for performing different kinds of work—for instance, the roll *i* having a rougher covering 85 than that of roll *h* and being adapted for buffing the tread-surfaces of heels, while the roll *h* is adapted for soles. It will be seen that the arrangement of the rolls is the most convenient possible for rapid work, for the operator standing in front of the machine can hold the shoe with its sole in contact with roll *h* as long as required and can then place the heel in engagement with roll *i* by a single simple movement of the hands downward 90 and rearward without requiring any alteration in the position of his body or manner of holding the shoe. Of course the order of operations may be reversed and work other than shoes operated upon by the rolls. 95

Previous to my invention buffing-machines have been made with a plurality of rolls arranged out of line and also laterally displaced from each other with respect to a vertical plane. Rolls of this character also have 105 been supported only at one end. Such machines are incapable of performing the best character of work in the minimum of time, since they either necessitate some loss of time and energy on the part of the operator by his stepping from one to the other or cause the work to be done in a less perfect manner by 110

reason of insecurity of the grasp of the operator on the work in cases where he does not shift his position, but moves only his hands, holding the work, from one roll to the other. 5 Such rolls also are not sufficiently rigid, as the end which is free will spring and yield when any pressure is put upon it. This difficulty is overcome by my construction, in which the rolls are held on shafts rigidly supported in bearings at both ends.

I claim—

1. A buffing-machine comprising a pair of side frames, and a pair of parallel rotatable abrasive buffing-rolls rigidly supported at 15 their opposite ends by said frames, said rolls being arranged in the same vertical zone, one of them being above and forward of the other, and both being a considerable distance above the base of the machine and adjacent each 20 other.
2. A buffing-machine comprising a pair of vertical side frames, a pair of horizontal shafts journaled rigidly in bearings in said frames and extending across the space between them, one of said shafts being above and forward of the other, and cylindrical buffing-rolls rigidly supported by said shafts respectively between the frames, both rolls being arranged in the same vertical zone, and 25 one of them being adapted for operating on the heel and the other on the sole of a shoe.

3. A buffing-machine comprising a pair of vertical side frames, a pair of horizontal shafts journaled in said frames and extending across the space between them, one of 35 said shafts being above and forward of the other, independent driving means for the respective shafts, cylindrical buffing-rolls rigidly supported by said shafts respectively between the frames, both rolls being arranged 40 in the same vertical zone, and each of them being adapted for operating on a separate part of the bottom of a shoe.

4. A buffing-machine comprising a pair of vertical side frames, a pair of horizontal 45 shafts journaled in said frames and extending across the space between them, one of said shafts being above and forward of the other, cylindrical abrasive buffing-rolls rigidly supported by said shafts respectively between the frames, both rolls being arranged 50 in the same vertical zone, and one of them being adapted for operating on the heel and the other on the sole of a shoe; an air-duct having inlet-openings adjacent said rolls, and means for exhausting air from said duct.

In testimony whereof I have affixed my signature in presence of two witnesses.

JOHN F. JESSEMAN.
